INDEX MEMBER AND ADJUSTABLE
INDICATOR TAB THEREFOR

George B. Meltzer, New York, N. Y., assignor to
Guide & Supply Co., Inc., New York, N. Y., a
corporation of New York

Application January 3, 1947, Serial No. 719,949

2 Claims. (Cl. 129—16.8)

1

This invention relates to index members and more particularly to an index member having an indicator tab secured thereto.

It is an object of my invention to provide an index member and an indicator tab wherein the tab may be secured on the index member in any one of a number of predetermined positions.

It is a further object to provide an indicator tab of simple construction and well suited to manufacture by mass production methods.

It is another object of my invention to provide means whereby my indicator tab may be securely locked in a selected position on the index member.

With these and other objects in view my invention will now be described in detail in conjunction with the appended drawings in which:

Fig. 1 is a perspective view of my invention as applied to a hanging folder;

Fig. 2 is a section thru 2—2 of Fig. 1;

Fig. 3 is a rear view of the indicator tab shown in Fig. 1;

Figs. 4—7 are each further modifications of the indicator tab;

Fig. 8 is an elevation of a modified form of index member for use with indicator members of the type illustrated in Figs. 1—7.

A detailed description now follows, wherein like reference characters refer to like parts throughout the several figures of the drawings.

With reference to Figs. 1—3, my invention comprises an index member exemplified as the fibrous hanging folder 10 of Fig. 1. Front and rear reinforcements 14 and 16, respectively, of sheet metal are disposed at the transverse edges of folder 10 in a conventional manner. A series of equally spaced perforations 18 are provided in the material of folder 10, such perforations being bounded by reinforcement 16 and having one side contiguous therewith. An inverted V-shaped indicator tab 20 bent at 21 and 22 and comprised of sheet metal or other ductile material is disposed astraddle the edge reinforcement 16. The legs 23 and 26 of tab 20 are provided with attachment means such as lugs 27 and perforations 28, respectively, the construction and arrangement being such that the lugs 27 are substantially aligned with corresponding perforations 28, and the spacing between lugs 27 is equal to that between the perforations 18 in the index member 10. Accordingly, it will be understood that the tab 20 with legs 23 and 26 suitably spread may be set astraddle edge 16 at any selected position, lugs 27 then being thrust thru respective perforations 18 and thence thru perforations 28 by manually squeezing legs 23 and 26 together,

2

thereby gripping edge 16 between them. In the forms shown in Figs. 1—5, lugs 27 are struck from the material of leg 23 and are offset therefrom and bent upwardly in a hook-like manner so that they overlap the lower edge of reinforcement 16, as shown. It will be understood that the structure is provided with sufficient play to achieve this effect by disposing the bend lines 21 and 22 with due regard to the vertical length of lugs 27 and the width of edge 16, so that after the lugs have been disposed thru the perforations 18, the tab 20 may be raised slightly to bring about the overlapping relationship between lugs 27 and reinforcement 16, as well as to align bend lines 21 and 22 with the top of reinforcement 16. The foregoing is an important practical feature, since by subsequently locking legs 23 and 26 against spreading, the indicator tab is firmly secured on reinforcing edge 16.

20 The form of locking means shown in Figs. 1—3 comprises a detent member such as the lock bar 32 which is essentially a flat strip of sheet metal or the like slidably retained on leg 26 by means of an elongated strap 35 formed of the material 25 of the leg. Bar 32 slides longitudinally with respect to strap 35, and is retained against loss by means of raised teats or bosses 38 pressed out of the material of the bar on either side of strap 35. The distance between bosses 38 is such as to 30 allow some pivotal motion of bar 32 to expedite manipulation in wedging the bar between lugs 27 and the outer surface of leg 26. It will be appreciated that the length of strap 35 is sufficient to permit bar 32 to clear perforations 28, by upward movement, at the time the tab 20 is being positioned on reinforcement 16, the bar being subsequently forced down into engagement with lugs 27 whereby the natural resiliency of the parts effects a rigidly locked condition.

40 The form of tab shown in Fig. 4 differs from that of Figs. 1—3 in the use of three lugs 27 instead of two. In such case two straps 35 are provided, each boss 38 being disposed to engage the inner edge of a respective strap. Obviously, lock bar 32 is extended to engage the three lugs 27.

45 Fig. 5 is a modification wherein a pair of lock bars 40 are pivotally retained on leg 26, being arranged to engage lugs 27 by pivotal motion from the dotted to the full line position.

50 Fig. 6 illustrates a further modification wherein straps 43 struck from the material of leg 23 (not shown) are utilized in a manner similar to lugs 27 of previous embodiments. In the present case, however, the straps 43 protrude thru leg 26 and a separable lock bar 45 of general U-shape is

disposed with its legs underneath the straps to lock the tab in place. Bar 45 may be comprised of a suitably bent wire rod.

Fig. 7 discloses an embodiment utilizing straps 43 struck from leg 23 (not shown) and protruding thru leg 26, wherein the openings provided by the straps are arranged vertically and aligned so that a separable lock bar 50 may be thrust there-through.

In Fig. 8 I have shown a modification of the index member to the extent that the perforations 18 in fibrous sheet 10 are brought into register with slots or serrations 53 in the lower edge of reinforcement 16. Such structural change affords a keying of lugs 27 (not shown) as a restraint against transverse motion against the metallic edges of serrations 53 which are normally more resistant to wear and tear than the fibrous edges of perforations 18.

It will be appreciated that many modifications of my teaching are possible and accordingly I do not intend to be bound by the specific illustrations hereinabove described except as set forth in the appended claims.

I claim:

1. An indicator member comprising a leg member, protruding attachment means carried by said leg member, a lock bar permanently carried by said indicator member and being movably engageable with said protruding attachment means, said indicator member having means for guiding said lock bar into engagement with said protruding attachment means, said means for guiding said lock bar comprising a strap formed from

the material of said indicator member, said lock bar being slidably retained by said strap.

2. An indicator member comprising a leg member, protruding attachment means carried by said leg member, a lock bar permanently carried by said indicator member and being movably engageable with said protruding attachment means, said indicator member having means for guiding said lock bar into engagement with said protruding attachment means, said means for guiding said lock bar comprising an elongated strap formed from the material of said indicator member, said lock bar being slidably retained on said indicator member by said strap, and means on said lock bar slidably engaging said strap to restrain said lock bar to substantially longitudinal motion with respect to said strap.

GEORGE B. MELTZER.
